JOHN E. BUCHER, OF COVENTRY, RHODE ISLAND, ASSIGNOR TO NITROGEN PRODUCTS COMPANY, OF PROVIDENCE, RHODE ISLAND, A CORPORATION OF RHODE ISLAND.

PROCESS FOR FIXING ATMOSPHERIC NITROGEN

1,138,196.

Specification of Letters Patent. Patented May 4, 1915.

Original application filed October 21, 1912, Serial No. 726,924. Divided and this application filed July 17, 1913. Serial No. 779,627.

To all whom it may concern:

Be it known that I, JOHN E. BUCHER, of Coventry, in the county of Kent and State of Rhode Island, have invented certain new and useful Improvements in the Process for Fixing Atmospheric Nitrogen, of which the following is a specification.

This invention relates to the fixation of nitrogen and more particularly to an improved process of preparing cyanogen compounds and derivatives therefrom, together with valuable by-products incident to the production of such a compound or compounds.

The process in question is essentially synthetic in character in its preferred form, and was suggested by my work on the synthesis of cyanids and on my processes for purifying and preparing metals, in which nitrogen plays an important part. Application for Letters Patent for these processes have been filed in the United States Patent Office, being there identified as applications Serial Number 676,399, dated February 8, 1912; Serial Number 690,886, dated April 15, 1912; Serial Number 710,758, dated July 22, 1912; and Serial Number 711,211, dated July 24, 1912. One of the equations representing the fundamental ideas of catalysis and reversible reactions upon which these four applications are based is the following:

The present application is a division of my application entitled "Process for fixing atmospheric nitrogen", filed October 21, 1912, Serial Number 726,924, which latter application relates to a process concerning conversion of carbonates and the like into cyanids, as per equation:

this parent application having been previously briefly referred to in my said application 711,211. The present divisional application relates more particularly to the synthetic production of cyanids, or the like, from an alkali metal or its equivalent supplied from such a compound as the carbonate of said metal when such compound is relatively remote from the reaction zone in

which the cyanogen compound is produced. In the said application of which this is a division is to be found a presentation of much of the art relating to cyanid production, and since this art is now of record in the parent application specific reference thereto, together with considerable of the matter set forth in the parent application relating to said art, or serving particularly to point out the essential differences between the known processes and that more especially referred to in the parent application have been omitted for brevity.

The hereinafter described process in its several aspects broadly aims to economically fix atmospheric nitrogen in a form whereby it may be utilized either with or without subsequent operations, according to the nature of the ultimate product sought.

In the accompanying drawings, which form a part hereof and in which like reference characters designate like parts throughout the several views, I have exemplified one form of apparatus in which my process may be effectuated. It is to be understood, however, that this apparatus is but one of many adapted to the purpose in question, and that I am not to be limited thereto in any way; nor indeed by specific steps or operation of my process as herein set forth, since I am aware that various changes and modifications may be made therein without departing from the spirit of my invention. In general I may state, therefore, that my said invention is to be regarded as limited only by the scope of the appended claims.

Description of apparatus.

Referring to the drawing: Figure 1 is a longitudinal vertical section of a muffle furnace with retorts in position therein. Fig. 2 is an end elevation of said furnace; the blast lamp being omitted for convenience of illustration. Fig. 3 is a fragmentary section of one of the pipes or retorts, the section being taken on line 3-3 of Fig. 1. Fig. 4 is a similar section of a retort adapted for the use of air in the process.

Brickwork or other suitable material may be employed in the construction of the muffle 1, and one or more iron pipes 2, serving as

retorts, may extend directly therethrough. Caps or unions 3, serve to connect the ends of the retorts to the pipes 4-5; those designated 4 being the pipes for supplying nitrogen or air as the case may be. The gases, notably carbon monoxid, evolved during the operation of the process are conveyed away via pipes 5. A blast lamp 6 or other suitable source of heat may be disposed in the 10 preferably open end of the muffle and this apparatus should, of course, be capable of heating the retorts up to the reaction temperatures employed; which will be herein-after very fully discussed.

15 Assuming that the process is to be conducted in such fashion as to permit the use of air, the latter is led in through pipes 4 and preferably first encounters one or more masses 7 of charcoal or other suitable oxygen consuming material. These masses preferably substantially fill the pipes at the points where they are disposed so that all of the air is obliged to pass therethrough. I prefer to interpose wire gauze spacing or 20 supporting screens 8, or the like, between the charcoal and the body of the reaction mixture 9 which is next encountered by the gases flowing through the pipe or retort; since it is desirable to keep the charcoal 25 away from the charge. During the course of the operation, the alkali compound initially supplied will be liquefied, and if the charcoal is in contact with the reactive mass or mixture, it may, by capillary action, or 30 from any other cause, remove a portion of such liquid compound from said mass and thereby reduce the yield. The mixture 9 preferably consists of pulverulent coke, graphite, charcoal, coal, or the like, very intimately 35 mixed with finely divided iron and sodium carbonate, or other inexpensive source of the metal forming the base of the cyanogen compound sought, or to be incidentally formed during the operation.

40 *Considerations of importance.*—Before considering the general reactions involved, I desire to state that I cannot too strongly emphasize the importance of considering what would appear, at first thought, to be 45 merely minor considerations, but certain of which considerations are vital to the success of the process, and the overlooking of which has apparently led to the practical failure of the repeated attempts to effectuate the same. 50 Non-observance of these considerations has led experimenters in this art to apparently partly succeed at one time, when by accident the conditions were propitious, and at other times to meet with total failure or with 55 only such success as would not justify continued operation of the process on a commercial scale.

The present work is based on a very large number of experiments, but I will here refer

particularly to three comparative ones. In 65 these experiments, sodium carbonate and graphite were heated, with nitrogen, in one case without the addition of a catalyst, in another with the addition of finely divided iron; and the two following equations are 70 very important in considering these cases.

In these three experiments, nitrogen, prepared by passing air through a tube containing red hot copper, was passed through a tube containing the reaction mixture.

Experiment 1: 10 grams of finely powdered graphite and 5 grams of sodium carbonate were heated in a current of nitrogen to between 920° and 940° C. for about fifty minutes, in a copper tube of one half inch diameter. At this temperature, there was a slow but steady evolution of carbon monoxid and some white fumes passed out of the tubes with this gas. These fumes imparted a steady though not very intense yellow color to the flame.

Experiment 2: Suspecting that these 90 fumes were due to the formation of the relatively volatile free sodium rather than to the volatility of the carbonate itself, I heated 5 grams of sodium carbonate with 30 grams of finely powdered iron in a similar 95 copper tube and in a current of nitrogen from 920° gradually up to 1000° C. for fifty minutes. In this test, the issuing gases did not impart the slightest trace of yellow color to the flame at any time, nor could carbon monoxid be detected. This latter experiment with iron and sodium carbonate alone (the graphite being omitted) proves that sodium carbonate is not sensibly decomposed by finely divided iron at 1000° C. nor is it 100 volatile enough to give a flame test at the end of the tube.

Experiment 1, (continued.) Upon cooling, the copper tube containing sodium carbonate and graphite showed a minute quantity of white material which had condensed on the cooler part of the tube; which deposit consisted at least partly of free metallic sodium. These facts show that at about 920° to 940° C., small quantities of sodium and 110 carbon monoxid are formed according to equation 3. When these two components attain a certain small vapor pressure, the reversible reaction comes to equilibrium. They are then swept along with the nitrogen 115 current and in turn another portion of the carbonate decomposes, thus tending to restore the vapor pressures necessary for equilibrium. The contents of the last mentioned tube were treated with water and 120 tested for sodium cyanid by means of the prussian blue test. Only traces could be detected even after the solution had stood for 125

a day. The experiment shows that graphite, sodium and nitrogen yield practically no cyanid when heated to the moderate temperature of 920°-940° C. in the absence of a catalytic agent. And even here it is possible that the copper in the tube or the impurities (Fe) in the graphite may have exerted some catalytic influence.

Experiment 3: A mixture of 10 grams of the graphite, 10 grams of finely powdered iron (*Pharmacopoeia Germanica IV*), and 5 grams of sodium carbonate were heated in an iron tube through which was passed a current of nitrogen. With the exception of adding iron as a catalyst and substituting an iron for a copper containing tube, all conditions were kept as nearly as possible like those of the first experiment. At a temperature of 920°-940° C. as measured by the pyrometer, there was, in this latter case, a steady absorption of nitrogen and the escaping gas burned with the characteristic blue flame of carbon monoxid. Nitrogen was still being absorbed at the end of fifty minutes when the heating was discontinued. The escaping gases contained no fumes nor did they show the slightest trace of yellow color when led into the burner flame, at any time during the experiment. This very sharp contrast with the experiment in which no catalyst was used shows that free sodium did not escape with the gases when iron was used. The contents of the tube were then treated with water and the resulting solution was titrated with silver nitrate. It was found that 60% of the sodium carbonate had been converted into cyanid. Under the conditions of this experiment, the velocity of the reaction was increased at least several thousand-fold, even at this relatively low temperature, by the catalytic action of the iron with a consequent transformation of 60% of the carbonate into cyanid in fifty minutes. A far more rapid formation of cyanid may be effected at, for example, higher temperatures, or by properly varying other conditions, as I shall hereinafter show. These and the further experimental results below mentioned, enable us to formulate a theory which is in accordance with the facts and is of great service in connection with the process.

By means of Experiment 1, in which iron was omitted, it was proved that reaction 3 takes place at 920° to 940° C. (and to a less extent at even lower temperatures). Now when comparatively small quantities of sodium vapor and carbon monoxid are present at this temperature, they tend to form sodium carbonate and carbon and thus reverse the reaction; establishing a chemical equilibrium. When no catalyst is present, the sodium does not unite rapidly with the

nitrogen and carbon, and consequently is 65 swept away by the current of nitrogen, so that we have very little formation of cyanid. When, however, finely divided iron is added to the mixture of carbon and sodium carbonate, the mixture being heated to the given 70 temperature as per Experiment 3, the iron will become carburized by dissolving some carbon; thus forming a solid solution of carbon in iron.

Theory of operation.—In chemical work, 75 it is often necessary to dissolve solids to make them reactive; and we also know that when substances are dissolved they very frequently become dissociated. These and many similar considerations point to the 80 conclusion that if the very complex and ordinarily comparatively inert carbon can thus be dissolved it will not only acquire mobility but perhaps may also become less complex; thus approaching the nascent condition. Iron is one of the best solvents known for carbon. Hence a solid solution, such as is obtained in the cementation process of manufacturing steel, will form very quickly at the surface of the metal; provided 85 that it is not already there, as in carburized iron. The conditions at this surface should be exceedingly favorable for chemical reactions and the above mentioned results obtained by the use of finely divided iron are 90 in accordance with this view.

Presumably a part at least of the operation takes place as follows: The small quantity of sodium vapor, formed according to Equation 3, and the nitrogen come in contact with the reactive surface of the carburized iron where they combine very quickly with the carbon dissolved in the surface of the iron, forming sodium cyanid. The vapor pressure of the gaseous sodium, is 105 thus reduced and consequently another portion of sodium carbonate decomposes to re-establish the equilibrium. This new portion of sodium vapor in turn combines with nitrogen and carbon at the surface of the 110 iron, which has meanwhile become recarburized by taking up carbon from the carbonaceous masses in contact therewith, or from the carbon in solution in the mass of iron. The iron hence acts as a catalyst by 115 undergoing a series of decarburizations and recarburizations; resulting in the efficient and continuous production of reactive carbon for the process. The very quick combination of sodium at this catalytic surface 120 reduces the concentration of the sodium vapor steadily; and thus materially aids in producing a continuous liberation of sodium with the consequent continuous formation of sodium cyanid. This very simple 125 theory, enables us to deal intelligently with the many conditions which influence the process. Evidently the first requisite is to

produce as efficient a catalytic or solution surface as practicable and to maintain its efficiency during the process. Even when the conditions of surface and contact appear to be correct or nearly so, at times a lapse of 10 or 15 minutes may occur before any vigorous reaction takes place. This may be due, in some cases, especially when working at a relatively low temperature, to the time, consumed in carburizing the reactive surfaces of the catalytic material; and probably also to changes in the relative disposition of fluid and solid constituents of the reactive mass by, for example, capillary action. The theory of the operation must therefore be borne in mind while the actual procedure is really a compromise between various factors. At one temperature one factor becomes dominant; at another temperature sometimes quite close to the first, another factor gains the ascendancy, and so on. Should my theory be faulty, which however I do not think is the case, it at any rate supplies a working hypothesis which enables us to achieve consistent and successful results.

Sources and condition of catalyst, etc.—A fine state of division of the iron exposes a large surface and hence acts favorably. Similarly a fine state of division of the carbon favors the quick carburization of the iron by providing thorough contact at, what I may term, the solution surfaces, or as I prefer to term it in the aggregate—surface. The iron and carbon should be mixed thoroughly for the same reason, except in those cases hereinafter referred to where the carbon is supplied through the agency of a vapor.

It is of importance to consider both the relative and the absolute size of the particles of carbon and iron as well as the extent to which they are in actual contact. The catalytic agent, *e. g.* iron, if used in solid form should be quite finely powdered or in such other form as to expose, or to render possible the exposure of, a relatively enormous solution surface. Particularly is this the case when the operation is conducted at temperatures materially below the eutectic point of the carbon-containing material. If the iron be a coarse powder, insufficient surface will usually be provided, under such conditions, to permit of the process being conducted efficiently. If, on the other hand, it is too finely divided, there is some tendency to pack too tightly and thereby prevent diffusion of the gases and vapors involved. On the whole, however, I prefer to divide the iron as finely as possible and to provide for diffusion in some suitable manner such as will be hereinafter indicated.

When the particles of catalytic material are relatively large, the surface is correspondingly small and the area of contact is likely to be too small for quick and efficient

renewal of the carbon content in the catalytic surface. Under the indicated conditions which I have found convenient in effectuating my process, when nitrogen and sodium were heated with iron, better results were, in general, obtained when the iron was relatively fine and the graphite comparatively coarse, than when the relative sizes were reversed, *i. e.* when the iron was coarse and the graphite fine. Thus iron *Ph. G. IV*, which is far finer than 100 mesh, gave very good results when used with graphite which had been passed through a one hundred mesh sieve but which on the whole was not nearly so finely divided as the iron. An even better result was obtained when said fine iron was used with graphite of 60 to 80 mesh. When, however, the graphite was of 20 mesh, used with this very fine iron the action was considerably slower. This series of tests, show, therefore, a distinct maximum for the graphite of intermediate coarseness; as was to have been expected since when the particles are too fine the mass lacks porosity and the nitrogen and sodium vapor cannot so easily penetrate the interior of the mass whereby to efficiently contact with the reactive surfaces (or as I herein broadly term it, reactive surface). On the other hand, when the graphite particles are too coarse the fine heavy particles of iron will tend to drop through the interstices and thus become segregated. The latter action would, in extreme cases, be equivalent to removing the catalyst from the field of action. I find that either of these two extremes may substantially result in the failure to produce cyanid. We should, further, not only consider the sizes of the particles, but also their other, general physical properties—*i. e.* shape, smoothness or roughness of surface, whether they are compact or spongy, regular or irregular in shape, whether they are adhesive at the temperature of the operation, etc. For example, if the particles are coarse, spherical or globular, nonadhesive and smooth, they favor segregation, while if, on the other hand, they are fine, irregular, rough and preferably slightly sticky or adhesive at the temperature of the operation, they obviously favor the contact and surface conditions when once established.

It is to be understood that while I regard finely divided iron as generally preferable for use in the process, in view of the possibility of increasing the potency of certain other factors hereinafter referred to, I do not wish to be limited to any particular size, condition or source of the catalyst or indeed of the size, condition or source of carbon for the same, except where, in certain of the appended claims such limitations are specifically introduced. For example, pulverulent iron may be produced directly in the reacting mass itself from iron com-

pounds or ores, such as oxids, carbonates, and the like, *e. g.*, hematite, magnetite, siderite and iron scale.

A mixture of finely powdered hematite, carbon and sodium carbonate may be prepared in such proportions as to leave the iron, graphite and sodium carbonate in favorable proportions for cyanid synthesis after the excess of graphite had reduced the hematite to metallic iron with the evolution of carbon monoxid. Under these circumstances the iron becomes reduced very readily (even if the solid carbon particles should not come in thorough contact with the iron ore, reduction would still take place completely because the molten cyanid formed reduces iron oxids with the utmost ease and even carburizes the iron at the same time): Further, if the temperature be sufficiently high, sodium vapor will be formed, according to Equation 3, which, of course, will act as a powerful reducing agent.

Iron scale (presumably Fe_3O_4) reduced very quickly and gave a very satisfactory yield of cyanid; leaving the resulting iron, after lixiviation of the cyanid, in excellent form for subsequent use with the process. Thus use may be made of a waste product (iron scale), or ore with the simultaneous production of cyanid, metallic iron, substantially nitrogen-free carbon monoxid, and with the removal, in part at least, of impurities such as sulfur, alumina, silica and phosphorus from the reacting mass. I consider that this may be of special interest in the iron and steel industry, especially as the process can be carried out in iron apparatus (which is not attacked by basic materials) at relatively low temperatures with basic reagents which hence tends to remove the two very troublesome elements, sulfur and phosphorus, as well as acid forming elements in general, including silicon. It presumably removes these elements as sulfids, phosphids or phosphates, silicates, aluminates, etc., and probably some nitrid forming elements in the form of nitrids. The low temperature, with consequent moderate reduction, to say nothing of the strong alkaline nature of the charge, tends to produce a very pure iron and at the same time affords a process for fixing atmospheric nitrogen.

Usually the iron thus obtained will be carburized but this may be decarburized very readily, as described in my said pending application, Serial No. 676,399, by means of the cheap sodium produced from cyanid, as described in my said application Serial No. 710,758.

Carbon.—The carbon may be supplied from a variety of suitable sources and in addition to those mentioned, which are solids, carbon supplying vapors may be used. Thus the hydro-carbons, *e. g.* petroleum, are available for use in certain cases. It is highly desirable usually to substantially completely exclude the oxygen of the atmosphere from participation in the reaction resulting in the production of cyanid, since oxygen either converts the cyanid formed to cyanate; or oxidizes the iron and results in the production of ferro-cyanids or the like upon subsequent lixiviation; or even worse, it may destroy the cyanid formed, with reproduction of carbonate.

The carbon has greater freedom of motion than one might at first expect. Its diffusion is not limited to mechanical motion due to the action of gravity, agitation of the mass, melting of solid material with consequent sintering, washing effect on the particles by currents of liquid due to surface tension, change of concentration, capillarity, distillation of liquids, etc. It is soluble in the iron, or the like, used as a catalyst, and can diffuse either in the form of solid or liquid solution. It may, in effect, be carried as liquid, vapor, or even as solid in the form of sublimate, by compounds such as cyanids, *e. g.* sodium cyanid. If these compounds come in contact with iron lacking in carbon, a reverse action may take place (Equation 4), thus helping to carburize the mass of iron. Indeed, this imparts a mobility to the carbon such as would be attained if the carbon could diffuse as a vapor, thus giving to the carbon, such as graphite, coke, charcoal, etc., in the tube, essentially the same kind of freedom that it would have if used in the form of hydrocarbons. I believe that this may be a matter of great importance under some conditions of cyanid synthesis as it does not require differences in temperature for its manifestation, *e. g.*

For example, in the above indicated disposition of masses of material, in the retort

(the brackets indicating the respective spaced masses and the tube being indicated

by dotted lines) we may form sodium cyanid in the usual manner at A. At B we may have decarburized iron. If now any cyanid be carried from A as a liquid, by distillation or by sublimation to B, the reverse equation 4, will take place at B; equation 4 being a reversible equation, the direction of the reaction depending on mass action, etc. The iron takes up the carbon from the cyanid with the liberation of sodium and nitrogen. This is practically equivalent to transferring the highly non-volatile graphite, in which form the carbon may be present in mass A, at temperatures substantially 10 in the vicinity of the eutectic point of iron and carbon, through the instrumentality of the intermediate formation of a volatile cyanid, to the mass B located in another portion of the tube or retort. Of course, the reaction 15 can be completed at A, first; thus getting rid of carbon monoxid separately, or, the two reactions may take place simultaneously. Also carbon monoxid and sodium form according to Equation 3, and, if the reaction 20 becomes reversed at the places where the temperature is lower or the concentration of carbon monoxid is greater, a mass of sodium carbonate and carbon will be deposited, in effect, as though the carbon had distilled as free carbon. This deposition 25 of carbon may help at times when the process is not proceeding as rapidly as might be desired.

Alkali metal.—The source of alkali metal or other base of the cyanogen compound formed, during the course of the process, is preferably some inexpensive compound such as sodium carbonate, sodium bicarbonate, sodium hydrate, or the like, but it is possible 10 to employ initially free alkali metal or its equivalent, and in those of the claims herein set forth which are of sufficient scope to be readable upon a process using initially free alkali metal or its equivalent as well as upon alkali metal other than initially free (in other words, where the alkali metal, or a volatile compound thereof, is supplied 15 from a source of the same, relatively remote from the reaction zone) are not to be deemed as being limited to such supply of alkali metal, or the like, from an existing compound of the same.

With respect to sodium bicarbonate I particularly desire to call attention to the fact 20 that I have successfully used the moist bicarbonate, which comes from the ammonia soda process; and this without previous drying. Indeed, very many impure alkali metal compounds which may result from various 25 technical processes can be converted into pure cyanogen compounds. For example, mixtures of alkali metal hydroxids, carbonates, acid carbonates, acetates, oxalates, etc., can be used directly if iron, oxids, or hydroxids, or

organic salts of iron, carbon or organic matter in general be present; and no contamination of the alkali metal cyanids can occur since the substances of the classes mentioned are so transformed in the process that the only negative radical remaining will be cyanogen. If more than one alkali metal be present, however, a mixture of alkali metal cyanids will result. When the cyanid obtained is to be transformed into ammonia as hereinafter described almost any other 75 impurities may be present without affecting the purity of the product, providing suitable precautions are taken. Alkali metal sulfates, can also be used with much advantage in my process. Potassium sulfate is obtained 80 extensively from the deposits at Stassfurt, Germany, while sodium sulfate is obtained in large quantity as a by-product from the action of sulfuric acid on sodium compounds, such as chlorid.

I find that in my process sulfates may readily be converted into cyanids by the following procedure: Pulverulent graphite and sulfates *e. g.* Na_2SO_4 or K_2SO_4 may be heated in iron pipes to temperatures suitable for cyanid formation. At this temperature the alkali metal sulfates are reduced rapidly to sulfid and carbon monoxid (which is substantially pure). Thus:

The sulfid may now be converted into carbonate even without removing it from the apparatus or separating it from the carbon with which it is mixed. This may be done 105 by allowing it to cool to a suitable temperature and then passing a current of moist carbon dioxid through the mass, or the water in suitable proportions may even be added directly to the mass containing the alkali metal sulfid and carbon before passing the carbon dioxid through the mass. The chemical action, in the case of sodium sulfid, may be expressed thus:

or

The mixture of sodium carbonate and carbon, thus obtained, is especially adapted for my process since, if desired, it may be mixed 125 with finely pulverized iron followed by subsequent heating with nitrogen at a suitable temperature to convert the alkali carbonate

into cyanogen compounds per Equation 4. The iron required for cyanid formation may also be added directly to the mixture of sodium sulfate and carbon, before heating.

I have shown that the transference of carbon from one separate mass to another in a tube or retort is possible, and will now consider the somewhat similar but not strictly analogous transference of sodium.

In this case a mass C of sodium carbonate and carbon (without iron) is heated in a current of nitrogen to produce sodium and carbon monoxide according to the following reaction:

15 Equation 3. If this current of the three gases, nitrogen, carbon monoxide and sodium be then passed through a mixture D of carbon and iron, cyanide forms, according to Equation 4, by absorption and combination.

20 of nitrogen and sodium at the catalytic surface of the carbon and iron; while the carbon monoxide passes out of the tube. I have

25 frequently used this mixture of carbon and iron with rather ineffective reaction mixtures to absorb the sodium vapor from the escaping gases, thus doing away completely with loss by volatilization, and the danger of explosions from free sodium when the masses were lixiviated. It is obvious too

30 that sodium carbonate, for example, may be distilled over, from a mass of the same into contact with the material presenting the reactive solution surface. I am of the opinion, however, that the bulk of the sodium

35 supplied by mass C to mass D passes over as free or metallic sodium in vaporous form. At 920° to 940° C. this sodium vapor would be formed quite slowly at C and be carried

40 be formed quite slowly at C and be carried to D by the nitrogen which at this temperature would usually make up the greater part of the gas. Mass C being now

part of the gas. Mass C being porous, as is also, of course, mass D, capillarity probably plays an important part in both cases. An extended film of the liquid source of the alkali metal hence forms the

the alkali metal hence forms on the carbon particles and this I shall, for convenience, term (whether here or, as in other cases, on the iron as well) a "reactive film", since it decomposes under the influence of

50 decomposes under the action of a suitable agent *e. g.* heat to liberate the alkali metal. Presumably if the film at C is very extended the sodium vapor quickly saturates the free space in the

space in the porous mass C, thus bringing about a condition of equilibrium. The rate of the sodium vapor would then be determined practically by the flow of the nitrogen current through the tube no matter

whether the masses in C and D were an inch

apart or many feet apart. For example, if the nitrogen were passed through a one half inch iron pipe at a temperature of 920-940° C. or even somewhat lower, at the rate of about 100 cc. per second, it would take a very long time to get a substantially quantitative yield of cyanid at D; and this in spite of the fact that cyanid formation, Equation 4, takes place practically instantaneously at this very efficient catalytic solution surface at D.

Equation 4 is apparently of the fifth order, when we consider it as taking place from right to left for the conditions at about 900° C., and the velocity of this retarding reaction would hence vary as the fifth power of the vapor pressure of the two gases, providing that it is of this order. Hence if the catalytic or other action were efficient enough to reduce this vapor pressure down to one tenth of its former value, the retarding effect would be decreased a thousand-fold. 70 75 80

I am aware that reactions of high order are rare (as stated by Nernst on page 560 of his *Theoretical Chemistry*, 4th edition, New York, 1904): but even if the reaction in question were only of the second order the 85 decrease of the retarding effect would yet be a hundred-fold; while in the lowest order, i. e. the first, said effect would still be ten-fold. This demonstrates that in any case the reduction effect is large and it may be, 90 indeed probably is, enormous, as I have indicated.

In the experiments above referred to, the rate of diffusion of the sodium vapor was about a million times as great as the velocity of the nitrogen current. Therefore when the components of the reacting mixture are finely powdered, the sodium molecules have such a short distance to travel that the rate at which the sodium comes in contact with the reactive solution surface is largely determined by the enormous molecular diffusion velocity rather than by that of the relatively slow sodium laden nitrogen current.

Let us now consider the masses C and D to be superimposed. In this case the par-

5 particles will be very close together, the masses will interpenetrate and cyanid formation will take place far more rapidly than where the effective supply of sodium is wholly dependent on the rate of flow of the nitrogen current rather than upon the velocity of the molecules of the alkali metal. For example, in the already cited Experiment 3, such interpenetration of the masses C and D (*i. e.* 10 such juxtaposition of the particles of iron and carbon, or such close juxtaposition of the reacting film and the reactive solution surface) was produced by thoroughly mixing the charge of iron, carbon and sodium carbonate previous to its introduction into the tube. The result was a yield of over 15 60% of the theoretically possible quantity of sodium cyanid, in fifty minutes. This experiment shows that the sodium is given off 20 in close juxtaposition with the catalytic solution surface of carbon in iron.

25 *Temperature.*—Temperature also must exert an enormous influence when we consider its various effects. It increases the velocities of chemical reactions enormously, and it also increases the rate at which the carbon goes into solution in the iron; as well as the rates of gaseous diffusion and development of vapors. The temperature of the 30 operation further intimately concerns the surface and contact conditions above referred to. When the finely pulverized iron and carbon mixture is heated to, or nearly to, the eutectic point (about 1150° C. although it may vary somewhat) it becomes sintered and partly welded or even melted 35 to globules. The surface is thus decreased and the mass of the iron becomes comparatively inert: the action nearly ceasing. Still 40 worse it may even drain away from the carbon source, especially if the materials are coarse. When portions of iron under these conditions are used over several times the yields drop from, let us say, 60% to about 45 40%; 18%; 7%; 3%, or even less than 1%. This probably accounts in large measure for the failure of many of the previous attempts.

50 The pulverulent iron may, if it has not been sintered into globules or worse, be used repeatedly, without repulverization. Its condition may even be improved by the operation since the treatment purifies the catalytic metal by removing sulfur, oxygen, and other impurities therefrom, as previously 55 noted. I am aware, however, that the carbon solution need not be solid and that the process may be made operative at temperatures considerably above the eutectic point of, for example, iron and carbon. For this 60 reason I do not wish to be limited to operations conducted at these relatively low temperatures except when in certain of the suspended claims limitations are introduced to that effect. I further do not wish to be restricted to any particular lower temperature 65

limit, except where in certain of the appended claims I have specifically referred to a temperature of 700° C. Indeed I contemplate effecting the process in certain cases at temperatures below even 700° C., since 70 rubidium and caesium carbonates, for example, and especially mixtures of these, or of one or more of these with sodium or potassium carbonate or analogously acting compounds permit of materially lowering the 75 temperature at which the nitrogen fixing reaction takes place (principally, I believe, by increasing the fluid circulation). By incorporating cyanids initially in the reaction mixture, the same end may also be attained 80 in a measure.

85 *Mobility of reaction mass or masses, and constituents thereof.*—In view of the foregoing, therefore, it is evident that the general mobility of the reaction mass and its components must be considered. Change of relative position of constituents of the reactive mass or masses may be due to the melting of alkali compounds (or even the 90 catalyst, to wit, iron, itself) with the consequent change in the position of the particles of carbon and iron, to the velocity of the nitrogen current, to the drainage of the molten compounds under the influence of gravity, to volatility, surface tension, capillarity and the like. From these effects, it is evident that the size and shape of the tube or retort, its inclination, the depth of the layer of reacting mixture, stirring of the charge, rotation of the tube or retort, (either continuously or at intervals,) etc., should also be considered. The nitrogen, of course, depends on the velocity of the gas current and the molecular diffusion rate under the 95 experimental conditions, for its chief source of motion. In a secondary way it might be carried, for example, in the form of liquid cyanid or cyanid vapors and these, by reverse action, might again liberate the nitrogen to some extent. The sodium may move through the mass in the form of molten compounds, or in the form of vapors of such compounds. It will also, after being liberated by the decomposition of the carbonate (or other compound thereof), Equation 3, or the 100 decomposition of cyanid, Equation 4, have the same freedom of motion and penetration as the nitrogen, *i. e.*, from the velocity of the gas current and the molecular diffusion velocity of the free sodium.

105 The effect of volatility has already been discussed under the mobility of the sodium and carbon in the reaction mixture. It may also be of great importance otherwise; as can be seen from the law of mass action and phase rule. It also causes circulation of liquids and vapors, washing action upon particles, and changes concentrations and 110 compositions of mixtures. Besides this, it may help to keep temperature conditions 115 120 125 130

uniform because of latent heat of vaporization. The flowing of molten matter, *e. g.* sodium carbonate, from whatever cause, must have much effect as shown by the 5 above considerations. Flowing of liquid may even cause segregation, by washing away particles of carbon or iron, and thus cause loss of efficiency. On the other hand it may be caused to, or may even inadvertently wash the particles into more 10 advantageous positions, thus causing increased efficiency. Also the molten materials may, as conditions determine, either flow away from or else toward the reacting mixture; 15 and this flow of liquid may therefore act either detrimentally or advantageously. For example, I have noticed that when conditions were not quite right, beneficial results were frequently obtained by simply rotating the tube containing the reaction mixture, about 180°. This is presumably due to the flowing of the liquid by gravity and the consequent surface changes. I regard the 20 effects due to surface tension or to relatively minute differences in surface tension, as well as to that phase of surface tension which is generally termed capillarity, and also the conditions which modify these, as of much importance.

30 As the composition of the molten alkali mixture is constantly changing during the process, the surface tension is presumably changed likewise, thus, tending to cause motion of the particles in a well known manner. The finely powdered, porous reacting mass affords exceptional opportunities for capillarity to exert its influence. The powdered mass of carbon and iron will take up by capillarity the liquid independently or 35 separately supplied thereto, or will similarly re-take up the liquid which may have drained by gravity to the lower portions thereof after the content of liquid remaining in the drained portions has been in whole or 40 in part removed; the action being not dissimilar to the way in which a lamp wick takes up oil. In this porous mass of carbon and iron the liquid comes in contact with the very large surface of the iron, and incidentally, of course, of the carbon; while 45 nitrogen can also diffuse to this surface very rapidly, which obviously tends under the prescribed conditions to favor the formation of cyanid; the films of liquid more or less rapidly being dissociated to yield the free sodium, which latter may either react where 50 liberated or elsewhere on the surface. Preferably the thinner the film the more readily can the nitrogen molecules penetrate it to 55 reach the reactive surface of the carbon supplying iron. When this film is too thick the nitrogen cannot well penetrate and the reaction is impeded. Further, the more extensive the film surface, the greater is the liberation 60 of free sodium per unit of time, together

of course, with a correspondingly accentuated evaporation of the liquid compound itself, or of its decomposition products. If too much molten liquid is present, the pores or interstices will, of course, be more or less 70 filled or choked therewith, thus preventing the required contact of the gaseous materials, such as nitrogen and sodium vapor, with the catalytic solution surface. We may regard the nitrogen as burning the carbon and 75 sodium to sodium cyanid, and if there be either insufficient catalytic solution surface or an inadequately reactive or insufficiently extensive film this peculiar combustion is retarded or in extreme cases may be almost 80 wholly prevented.

The above considerations concerning the mobility, especially that due to capillarity, within the reacting mass led me to make a considerable number of experiments of 85 which the following are typical: An efficient mixture of 40% of graphite of 100 mesh, 40% finely powdered iron (*Ph. G. IV*), and 20% of freshly ignited sodium carbonate was prepared. A flat bottom iron retort 70 mm. 90 by 10 mm. was attached to a long piece of wire so that it could be inserted into a long pipe which was heated to the desired temperature and through which a current of nitrogen was passing.

95 Experiment 4: One half a gram of the above reaction mixture containing carbon, iron, and sodium carbonate was tamped into the retort in a uniform layer. The retort was now pushed into the tube which was 100 heated to 1070° C. Not more than a minute was allowed for it to come to the reaction temperature, and it was then allowed to remain for five minutes more in the heated nitrogen. It was then withdrawn to the cold 105 part of the tube and allowed to cool in the current of nitrogen. Upon lixiviation, so little cyanid was found that it could not be titrated accurately with silver nitrate solution. (This experiment was repeated with 110 the exception that the tube was heated to 1000° C.—the result being the same.)

Experiment 5: The retort was again charged with one-half gram of aforesaid mixture of sodium carbonate, iron and 115 graphite, and six-tenths of a gram (an equal volume, therefore an equal depth of layer) of a mixture of equal parts of the 100 mesh graphite and the iron (*Ph. G. IV*) was tamped on the surface of the reactive mixture containing the sodium carbonate. This was pushed into the tube containing nitrogen 120 heated to 990° C. As before five minutes was given for the reaction. The yield of sodium cyanid was 25% of that theoretically possible.

Experiment 6: The operation was now repeated substantially as per Experiment 4, at 990° C. but without the tamping material. Here the quantity of cyanid formed was too 125

small to be titrated with silver nitrate solution.

Experiment 7: This experiment was exactly like Experiment 5 with the exception that twice as much (one and two-tenths grams) of the above carbon-iron tamping mixture was used, *i. e.* the layer of tamping material was twice as deep as that used in Experiment 5. In this case, I found that about 50% of the sodium carbonate had been converted into sodium cyanid in five minutes at 990° C.

Experiment 8: This experiment was like Experiment 7 with the exception that the one and two-tenths grams tamping mixture were placed in the bottom of the retort and the five tenths grams reaction mixture formed the upper layer. The result was substantially the same as that of Experiment 7, *i. e.* fully 50% of the sodium carbonate was converted into sodium cyanid in five minutes at 990° C. (At another time the same yielded fully 40% in two minutes.)

Experiment 9: In this case the quantities of material used were exactly those in the preceding Experiment 8, but they were thoroughly mixed instead of being used in layers. In this particular experiment the yield of cyanid was about 40% of the theory, in five minutes at 990° C.

Experiment 10: This experiment was practically a repetition of that described under Experiment 6, and is cited merely as an exception, since in this case, a small yield of cyanid, to wit, 15% was obtained, which demonstrates that even under what appear to be identical conditions, some variations in yield may occur. In the case in point, the cyanid formation may have been due to some condition such as lack of uniformity in the mixture, all parts not being uniformly saturated, or in other words, some sufficiently effective film surface was present which during the course of the operation, once being present, would tend to extend itself, due to capillary action, or circulation induced by changes in composition in the liquid phase.

I have stated in the preceding experiments, where yields were obtained, that these yields were "fully" 50%, etc. This phraseology is used advisedly since the yield was obtained by titration and in each case more or less of the cyanid was volatilized during the course of the operation, especially owing to the extent of the surface present from which volatilization could take place. At different times Experiment 8 was repeated with the exception that the period of operation was extended to one-half hour. In each case substantially no cyanid was found in the residue in the retort or tube, while further but little, if any, carbonate remained, which in view of the preceding shorter term operations indicated that cyanid had been formed and had thereafter volatilized.

The following experiments are of interest as showing the effectiveness of the process at relatively low temperatures:

Experiment 11: This experiment was substantially like Experiment 8 with the exception that in the reaction mixture, one half of the sodium carbonate was replaced by potassium carbonate. The temperature of the operation was 840° C. and the cyanid yield in the residue, upon titration, and at the expiration of a thirty minute run was fully 45%. In this connection it may be of interest to note that the melting point of sodium carbonate is apparently about 860° C. while that of potassium carbonate is about 880° C. The eutectic point of the mixture is about 690° C.

Experiment 12: This experiment was a repetition of Experiment 11, except that the temperature of the operation was 780° C. and the time—forty minutes. The yield by titration was 22%.

Experiment 13: This experiment was a repetition of Experiment 12, save that the temperature was 730° C. and the time forty-five minutes. Yield by titration somewhat over 2%. Obviously as the temperature was lowered the cyanid formation per given unit of time decreased. Correspondingly, other things being equal, more elevated temperatures afford markedly greater yields per unit of time. Thus I have converted 45% of a given quantity of sodium carbonate into cyanid in two minutes, and over 80% in five minutes at 1060° C.

The efficiency of the catalyzer in lowering the temperature of cyanid formation and increasing the rate of its formation is even more strikingly shown by comparing the foregoing with the following statement of Dr. Ewan, in *Thorpe's Dictionary of Applied Chemistry*, revised edition, vol. 11, 1912, page 196:

"A few temperature measurements which the writer made with a platinum rhodium thermocouple showed that potassium vapor is first evolved from a mixture of potassium carbonate and charcoal at about 1350° and that the formation of cyanid takes place very slowly at this temperature, the potassium cyanid volatilizing for the most part."

Experiments 4, 6 and 10 were made with the very efficient reaction mixture above referred to, but their yields were unsatisfactory, at least when compared with the remaining experiments in the series. I may here observe, though, that the mixture used in these three experiments (4, 6 and 10) should give very satisfactory results when heated in twenty-five gram lots in a half inch gas pipe to 990° C. with the nitrogen.

Experiments 5, 7, 8 and 9 gave very rapid conversion of carbonate into cyanid. Presumably in Experiments 5 and 7 the carbonate (sodium) melted and then penetrated

by capillarity into the upper layer of tamping material, there to be rapidly and efficiently converted into cyanid. In Experiment 8 where the reacting mixture constituted the upper layer, the same result was attained by means of the capillary forces aided by gravity, while in Experiment 9 the same result as in 8 was attained by thoroughly mixing the materials before they were tamped into the retort. Also when the very efficient reactive mixture was used in the thinner layer the yields varied from almost nothing (4 and 6) to a comparatively poor yield in 10; presumably because the slight depth did not permit of sufficient drainage of the molten sodium carbonate from the upper layers of the mixture so as to provide suitable reaction conditions. On the other hand when a larger quantity, such as twenty-five grams was tamped into a one-half inch iron pipe, presumably a portion of the molten carbonate in the upper portions of the mixture drained to the lower portions so as to leave conditions in the upper part of the mass very favorable for cyanid formation thereby automatically producing conditions substantially similar to those provided intentionally in Experiments 5 and 7.

Use of apparatus shown by way of exemplification.—Assuming now, that the conditions prescribed have been observed in the disposition of material in the furnace shown in the accompanying drawing, and that an adequate current of nitrogen is flowing through the tubes 2, each of the latter having in this case a mass 9 of intimately mixed finely powdered iron, sodium carbonate and graphite in place therein. The actions and reactions take place as above described, sodium cyanid is formed in the interstices of the masses 9 and carbon monoxid gas flows off together with some excess nitrogen, through the tubes 5. It is to be understood, of course, that it is possible to operate quantitatively, so that substantially all of the nitrogen, carbon and alkali metal compound are converted directly into cyanid; and all of this can be done below the melting point of copper. The cyanid which may be obtained from the residue of the masses 9 is substantially 100% pure; and as cyanid is exceedingly soluble in water, lixiviation affords a convenient means for separating it from the residues of the reaction. Air may be used in lieu of nitrogen and the arrangement of materials and parts shown in Fig. 4 has been found a convenient one in such cases. Save for the provision of the oxygen consuming charcoal 7, and separating screen 8, the operation and apparatus is substantially the same as in the case just discussed. It may be well to note, however, that when using air is it advisable to operate at a slightly higher temperature, say 50° C., than when using nitrogen. The charcoal com-

bines with the oxygen content of the inflowing air so that a mixture of carbon monoxid and nitrogen, with possibly some carbon dioxide passes on to the reactive mixture and the nitrogen reacts therewith, as before. The heat necessary can be produced in the furnace tube or retort itself, thus almost entirely avoiding wear and tear on the apparatus.

Time factor.—In the art of cyanid synthesis, we find frequent references to the yields obtained, but much less often to the time required for effecting the changes. I wish to emphasize the very great importance of this time element and have aimed constantly in developing my process to make it an expeditious one. When it is considered that the cost of labor, wear and tear of apparatus, interest charges, loss of heat by radiation, conduction, and hot flue gases are, in general, direct functions of the time an operation requires; we realize that the time factor may become, sometimes, of even greater importance than the ultimate or practicable yield. For example, the time given for certain processes is sometimes ten hours or more, with alleged yields of perhaps 50% or much less, and under very drastic temperature conditions. My process affords far greater yields, and at very moderate temperatures, in from two to twenty-five minutes according to the conditions selected. In other words, my process will easily produce as much cyanid in several days as such processes can in a year. From this, it is evident that such an expeditious process is an enormously advantageous one even if it were equally affected by the above items of expense, which, however, is not the case. It is also evident that in many cases it is desirable to sacrifice the yield somewhat providing a considerable saving in time will result. Thus it may be found advantageous in certain cases to operate for a short time only upon a given mixture with the object of producing, let us say, a yield of 50%; thereafter removing the cyanid formed in any suitable manner and re-using the residue either alone or mixed with fresh material or materials, e. g. iron and sodium carbonate, as desired.

Resumé.—To epitomize, therefore, the features of the process which, when observed, lead to consistent results and commercial success in the production of cyanid.

(a) A material, e. g. iron, capable of readily dissolving carbon, must be employed as a catalytic agent.

(b) This material should be present in such quantity and should be in such condition as to afford an abundant solution or reactive surface.

(c) This surface should be maintained. By this I do not mean that necessarily the same identical surface must be maintained, although even this is preferable, but that the

extent of available surface considered as a whole should be substantially maintained and that the carbon present therein should be maintained in sufficient quantity to permit of an energetic and practically continuous reaction taking place between said carbon and the nitrogen and free, or probably free, alkali metal.

(d) The carbon should be present in such quantity and so disposed with respect to the carbon dissolving metal or agent that the reactive surface of the latter may be adequately and substantially continuously supplied. To this end also proper contact must be effected and maintained between the carbonaceous material and said metal, unless the latter be initially sufficiently carburized to permit of continuous operation for a sufficiently extended period of time.

(e) The source of the alkali metal, or base of the compound sought, may either be intimately mixed with the catalytic material or otherwise. The essential feature to be observed is that the metallic vapor molecules must be developed or be supplied in adequate quantity and must either be in contact with or be able to make contact with the carbon supplying solution surface at the same instant as the nitrogen molecules.

(f) The reactive solution surface must not only be extensive and properly carburized but it must be accessible to the molecules of the gases or vapors participating in the reaction. In other words, it must not be clogged up or covered with too thick films of liquid. When, therefore, the source of the base of the cyanogen compound sought is a material which is molten at the temperature of the operation, *e. g.* sodium carbonate, and this liquid is present in excess, a sufficient extent of effective solution surface must still be preserved by affording proper drainage facilities, or the equivalent thereof.

(g) The mass should be sufficiently porous to permit of the, at least, moderately free passage of nitrogen therethrough whereby not only to supply nitrogen in adequate quantity to a sufficient extent thereof to favor a rapid production of cyanid; but, also, to sufficiently dilute and preferably to even dislodge, or sweep away, the deleterious, inert carbon monoxid from the reaction surfaces.

(h) The temperature of the operation must be such as to afford the requisite molecular activity. The principal point to be observed in connection with the temperature is that at temperatures materially below a fairly bright red heat the contact relations existing between the catalytic material and carbon must be more intimate and complete and the effective reactive surfaces more extensive than at higher temperatures. In other words, what we lose in temperature, must be made up in some other way. The

lower temperatures of course, tend to prolong the life of the apparatus.

General remarks.—Owing to the numerous possibilities of the process, I have only described some of the more important steps involved, hence I wish to be limited only by the general spirit of the above disclosures and by the appended claims. For convenience, I have described most of the experiments, and written the corresponding equations, for sodium compounds; but these descriptions are intended to apply to alkali compounds generally, and, where applicable, to metals capable of performing like functions in the process.

In certain of the appended claims I have used the term "vapor" and in such cases where not otherwise specifically limited or restricted, this term is to be regarded as of sufficient breadth to cover, for example, both alkali metal vapor and the vapor of an alkali metal compound, *e. g.* sodium carbonate, etc.

Having thus described my invention what I claim is:

1. The process of fixing atmospheric nitrogen which comprises effecting a liberation of alkali metal vapor from a compound of the same, substantially preventing the liberated metal from exercising a reaction retarding vapor pressure upon the residue of said compound by intermingling a current of free nitrogen with the so liberated alkali metal and reacting upon the mixture with carbon held in solution in a mass of catalytic material disposed at a point relatively remote from the place where said alkali metal is liberated, to form a cyanogen compound of said alkali metal.

2. The process of fixing atmospheric nitrogen which comprises effecting the liberation of an alkali or alkaline earth metal capable of acting as the base of a cyanogen compound to be formed while said nitrogen is being fixed, from a compound of said metal, sweeping the liberated metal in vaporous form toward a separate mass of catalytic material containing carbon in solution, by means of a current of free nitrogen and reacting upon the mixed nitrogen and metal vapor with said carbon in solution to directly form a cyanogen compound of said alkali metal.

3. The process of fixing atmospheric nitrogen which comprises effecting the liberation in vaporous condition of an alkali or alkaline earth metal, from a mass of material containing said metal as one of the constituents thereof, passing a current of free nitrogen in contact with said mass and thereby forming a mixture of nitrogen and the vapor of said metal, conveying said mixture into intimate contact with a mass of catalytic material containing carbon in solution, and reacting upon said carbon with said mixture.

to form a cyanogen compound of said light metal.

4. The process of fixing atmospheric nitrogen which comprises bringing free nitrogen and the vapor of an alkali or alkaline earth metal, capable of acting as the base of a cyanogen compound to be formed while said nitrogen is being fixed, simultaneously into intimate contact with carbon dissolved in a heated mass of catalytic material having an extended solution surface, and effecting a direct reaction at said surface between said metal, nitrogen and carbon to synthetically form said cyanogen compound.

15 5. The process of fixing atmospheric nitrogen which comprises bringing an intimate mixture of free nitrogen and the vapor of an alkali or alkaline earth metal, capable of acting as the base of a cyanogen compound to be formed during the course of said process, into close contact with an extended surface of catalytic material containing carbon in solution, reacting at said surface upon the dissolved carbon with said metal and nitrogen to synthetically form said cyanogen compound, and continuing said reaction by abundantly supplying said surface with fresh carbon as the content of dissolved carbon therein is reduced by said reaction.

30 6. The process of fixing atmospheric nitrogen which comprises bringing an intimate mixture of free nitrogen and the vapor of an alkali or alkaline earth metal, capable of acting as the base of a cyanogen compound to be formed during the course of said process, into close contact with an extended surface of catalytic material containing carbon in solution, reacting at said surface upon the dissolved carbon with said metal and nitrogen to synthetically form said cyanogen compound, and maintaining the efficiency of said surface both with regard to its extent and to the carbon content thereof.

45 7. The process of fixing atmospheric nitrogen which comprises bringing free nitrogen and an alkali or alkaline earth metal in molecular condition which is capable of acting as the base of a cyanogen compound to be formed while said nitrogen is being fixed simultaneously into intimate contact with carbon dissolved in a heated mass of catalytic material having an extended solution surface, and effecting a direct reaction at said surface between said metal, nitrogen and carbon to synthetically form said cyanogen compound.

80 8. The process of fixing atmospheric nitrogen which comprises bringing free nitrogen and an alkali or alkaline earth metal in molecular condition which is capable of acting as the base of a cyanogen compound to be formed while said nitrogen is being fixed, simultaneously into intimate contact with carbon dissolved in a heated mass of finely divided catalytic material having an ex-

tended solution surface, and effecting a direct reaction at said surface between said metal, nitrogen and carbon to synthetically form said cyanogen compound.

9. The process of fixing atmospheric nitrogen which comprises bringing free nitrogen and an alkali or alkaline earth metal in molecular condition which is capable of acting as the base of a cyanogen compound to be formed while said nitrogen is being fixed, simultaneously into intimate contact with carbon dissolved into a heated mass of iron having an extended solution surface, and effecting a direct reaction at said surface between said first mentioned metal, nitrogen and carbon to synthetically form said cyanogen compound.

10. The process of fixing atmospheric nitrogen which comprises bringing free nitrogen and an alkali or alkaline earth metal in molecular condition which is capable of acting as the base of a cyanogen compound to be formed while said nitrogen is being fixed, simultaneously into intimate contact with carbon dissolved in a heated mass of a metal capable of dissolving carbon and having an extended solution surface, and effecting a direct reaction at said first mentioned metal, nitrogen and carbon to synthetically form said cyanogen compound.

11. The process of fixing atmospheric nitrogen which comprises effecting the liberation of an alkali or alkaline earth metal capable of acting as the base of a cyanogen compound to be formed while said nitrogen is being fixed, from a compound of said metal, disposed in the form of an extended film, sweeping the liberated metal in vaporous form toward a separate mass of catalytic material containing carbon in solution, by means of a current of free nitrogen and reacting upon the mixed nitrogen and metal vapor with said carbon in solution to directly form a cyanogen compound of said alkali metal.

110 12. The process of fixing atmospheric nitrogen which comprises effecting a vigorous reaction between free alkali or alkaline earth metal atmospheric nitrogen substantially free from oxygen, at least when participating in the reaction, and carbon in solution in a mass of catalytic material capable of favoring said reaction, at an extended surface of said catalytic material, whereby to directly form a cyanogen compound, and continuing said reaction by supplying fresh carbon to said surface to replace that removed therefrom by said reaction.

125 13. The process of fixing atmospheric nitrogen which comprises effecting a vigorous reaction between free alkali or alkaline earth metal atmospheric nitrogen substantially free from oxygen, at least when participating in the reaction, and carbon in solution in a mass of solid catalytic material capable

of favoring said reaction, at an extended surface of said catalytic material, whereby to directly form a cyanogen compound, and continuing said reaction by supplying fresh carbon to said surface to replace that removed therefrom by said reaction.

14. The process of fixing atmospheric nitrogen which comprises effecting a vigorous reaction, at a temperature in excess of 500°

10 C. but below a temperature at which the process becomes ineffective, between free alkali or alkaline earth metal, atmospheric nitrogen substantially free from oxygen, at least when participating in the re-

15 action, and carbon in solution in a mass of catalytic material capable of favoring said reaction, at an extended surface of said catalytic material, whereby to directly form a cyanogen compound, and continuing said

20 reaction by supplying fresh carbon to said surface to replace that removed therefrom by said reaction.

15. The process of fixing atmospheric nitrogen which comprises treating a compound, which contains an alkali or alkaline earth metal capable of acting as the base of a cyanogen compound to be formed while said nitrogen is being fixed, to obtain a vapor therefrom, by subjecting said compound

to heat and to capillary action, the latter 30 whereby to form an extended film surface of said first mentioned compound at which said vapor is produced, and thereafter bringing said vapor into contact with a mass of catalytic material containing carbon in solution 35 in an extended surface of said material and vigorously reacting upon said vapor simultaneously with free nitrogen and said carbon, to form said cyanogen compound.

16. The process of fixing nitrogen which 40 comprises bringing initially free nitrogen into contact with carbon dissolved in catalytic material presenting an extended, rough, solution surface, combining the dissolved carbon present in said surface with 45 said nitrogen and with an alkali or alkaline earth metal capable of acting as the base of a cyanogen compound to be formed while said nitrogen is being fixed, to form said compound; and maintaining said solution 50 surface effective by supplying fresh carbon thereto.

In testimony whereof I have affixed my signature, in the presence of two witnesses.

JOHN E. BUCHER.
